HAND PUPPET IN THE FORM OF A DRAGON'S HEAD

Michael Bacarella, Jr., 200 N. Lima,
Burbank, Calif. 91505

Filed Feb. 18, 1975, Ser. No. 550,716

Term of patent 14 years

Int. Cl. D21—01

U.S. Cl. D34—2 R

Fig. 1

Fig. 2

Fig. 3

Fig. 4

FIG. 1 is a perspective view of a hand puppet in the form of a dragon's head showing my new design.

FIG. 2 is a front view thereof.

FIG. 3 is a rear view thereof; and

FIG. 4 is a bottom view thereof.

I claim:

The ornamental design for a hand puppet in the form of a dragon's head, as shown.
